UNITED STATES PATENT OFFICE.

ROY EDWIN WHEELER, OF KITTITAS, WASHINGTON.

PUMP-CYLINDER PROTECTOR.

1,167,670.

Specification of Letters Patent.

Patented Jan. 11, 1916.

Application filed January 25, 1915. Serial No. 4,272.

To all whom it may concern:

Be it known that I, ROY EDWIN WHEELER, a citizen of the United States, residing at Kittitas, in the county of Kittitas and State of Washington, have invented certain new and useful Improvements in Pump-Cylinder Protectors; and I do declare the following to be a full, clear, and exact description of the invention, such as will enable others skilled in the art to which it appertains to make and use the same.

This invention relates to improvements in protectors for pump barrels or cylinders and which are commonly known as rivet catchers and are designed to catch the rivets that frequently become disconnected from the joints between the parts of the rod employed to move the piston rod or working valve up and down, and which rivets when they become disconnected drop down into the working barrel of the well and seriously interfere with the proper working of the pump or valves and cause injury to the valve rod or pump and other portions of the pump by cutting and wearing the same and at times become lodged between the working parts of the pump or valves and the working barrel.

The object of the invention is to provide a simply constructed and efficient device of this character which may be readily applied to the plunger rod of a pump and which will offer very little resistance to the reciprocation of said rod.

With this and other objects in view, the invention consists of certain novel features of construction, combination and arrangement of parts as will be more fully described and claimed.

In the accompanying drawings Figure 1 represents a longitudinal vertical section through a pump barrel showing this improved protector in side elevation therein; Fig. 2 is a longitudinal vertical section through the protector; Fig. 3 is a horizontal section taken on the line 3-3 of Fig. 2; Fig. 4 is a similar view taken on the line 4-4 of Fig. 2. Fig. 5 is a similar view on line 5-5 of Fig. 2.

In the embodiment illustrated a pump barrel or cylinder 1 is shown having the usual piston or plunger rod 2 mounted to reciprocate therein and both of which may be of any suitable or desired length. The rod 2 has the usual valve 3 mounted thereon and disposed on said rod just above this

valve is the catcher or protector constituting this invention. This catcher comprises a hollow inverted truncated cone-shaped cup 5 preferably constructed of sheet metal and having a cylindrical sleeve 6 at its lower smaller end of a size to encircle and closely fit the rod 2 and it is secured to said rod by a clamping collar 7. This conical cup 5 is preferably struck out of a sheet of metal 65 plate and the side edges thereof are overlapped and secured together by riveting or in any other suitable manner, the seam of the lower end of the cup and of the sleeve 6 being left open to provide for expansion and contraction. The wider upper end of the cup is of a diameter slightly less than that of the cylinder 1 to which it is to be applied so as to permit the cup to move freely in the cylinder without contact therewith. A 70 brace 8 extends transversely across the upper end of the cup 5 and has an outwardly bowed central portion 9 adapted to encircle one-half of the rod 2 and which has apertures 10 at the opposite sides of said bowed 75 or looped shaped portion 9 to receive a co-operating clamping member 11 herein shown U-shaped with the free ends of its legs threaded to receive clamping nuts 12 after said legs have been passed through the apertures in the brace. The walls of this cup 5 are provided with a plurality of openings 80 for the passage therethrough of water or other liquid to prevent interference with the operation of the pump and these openings 85 are herein shown in the form of longitudinally extending laterally spaced slits 13 arranged around the periphery of the cup. 90

The inverted cone shape of the cup 5 facilitates its downward passage through the cylinder 1 offering a minimum resistance and the arrangement of the slits therein for the passage of the water permits it to move in the opposite direction without presenting much resistance.

From the foregoing description it will be obvious that should any rivets or other particles become loosened and drop down in the cylinder they will be caught by this cup 5 and held therein, thereby preventing them 105 from injuring any of the parts of the pump and they may remain in the cup indefinitely until such time as it is desired to remove them.

I claim as my invention:

A protector for pump cylinders comprising an inverted truncated cone shaped cup

open at both ends and adapted to encircle a pump rod, said cup having a longitudinally extending opening in its lower end to provide for expansion and contraction, 5 means for clamping the lower end of said cup to a rod, a brace extending transversely across the larger end of said cup and having a bowed central portion with apertures on opposite sides of said bowed portion and U-shaped clamping member having the legs

thereof mounted in said apertures, and means for fastening said legs in said apertures.

In testimony whereof I have hereunto set my hand in presence of two subscribing 15 witnesses.

ROY EDWIN WHEELER.
